UNITED STATES PATENT OFFICE.

GEORGE W. HENRY, JR., OF PHILADELPHIA, PENNSYLVANIA, ASSIGNOR TO H. G. DAVIS MANUFACTURING COMPANY, OF PHILADELPHIA, PENNSYLVANIA, A CORPORATION OF PENNSYLVANIA.

PIN-TAG.

1,358,546.

Specification of Letters Patent.

Patented Nov. 9, 1920.

Application filed March 7, 1917. Serial No. 153,040.

To all whom it may concern:

Be it known that I, GEORGE W. HENRY, Jr., a citizen of the United States, residing in Philadelphia, Pennsylvania, have invented certain Improvements in Pin-Tags, of which the following is a specification.

One object of my invention is to improve a pin tag or ticket so that the projecting pins or prongs will be at or near the edge 10 of the ticket.

A further object of the invention is to design the pin so that a comparatively thin ticket can be used.

A still further object of the invention is 15 to design the pin ticket so that it can be accurately fed to a printing machine after the pin is in place.

In the accompanying drawings:

Figure 1 is an inverted perspective view 20 of my improved pin ticket, or tag;

Fig. 2 is a plan view;

Fig. 3 is an inverted plan view;

Fig. 4 is a longitudinal sectional view on the line 4-4, Fig. 2;

Fig. 5 is a perspective view showing the pins beyond the edge of a ticket;

Fig. 6 is a perspective view showing a slightly different arrangement of the clamping member of the pin; and

Fig. 7 is a view of my invention applied to a folding ticket.

Referring to the drawings, 1 is the tag, or ticket. 2 is a pin, bent as clearly shown in Figs. 1 to 4, having prongs 3. The pin is 35 made from wire shaped to form two prongs, the wire being bent at x to form a flat body portion 4, which rests on the face of the tag, or ticket, the pin being previously passed through openings y - y in the tag some distance back of the edge v . The connecting portion 5 of the pin is preferably curved, as shown, and is located on the opposite side of the ticket from the body portion 4, and the ticket is clamped between the portion 5 and the body portion 4, while the prongs 3 are located at the edge v of the ticket.

By this construction, the pin is passed through the ticket some distance from its edge and the ticket is clamped between the

two portions of the pin, and, consequently, 50 a comparatively light weight paper can be used for the body of the ticket. By having the prongs at the edge of the ticket, the face of the ticket can be printed after the pin is in place, as openings can be provided in the 55 platen of a printing press for the reception of the pins.

Furthermore, by this construction, a greater surface can be occupied by the 60 printed matter than where the prongs are some distance back of the edge of the ticket.

In Fig. 5, I have illustrated a modification in which the prongs are located slightly beyond the edge of the ticket.

In Fig. 1, which is an inverted view of the 65 tag, or ticket, the prongs 3 and the body portion 4 are on the same side of the ticket, while the curved portion 5 is at the face of the ticket.

In Fig. 6, the body portion is at the face 70 of the ticket and the prongs and the curved portion are at the back of the ticket.

In Fig. 7, 1^a is a form of ticket which is 75 folded at 6 and the pin 2^a is attached to one edge of the ticket, as shown, and the prongs 3^a, when the ticket is folded, pass through perforations 7 in the ticket and are bent over, while the tongue 8 is passed through a slot 9 in the body portion of the ticket and covers the points of the pins.

By this construction, accuracy is assured 80 and the pins can be bent down toward each other so as to extend back of the paper between the perforations or can be bent outward, as desired.

I claim:

A pin tag or ticket having a securing pin attached thereto, the arms of said pin projecting through the tag intermediate its length, extending in parallel relation from 90 said point of projection to the edge of the tag and being bent from said latter point at right angles to the face of the tag, thereby forming an article of this character which may be placed in a package one upon another without offset.

In witness whereof I affix my signature.

GEORGE W. HENRY, JR.
